(No Model.)

E. J. REMILLON.

SWITCH STAND.

No. 368,169.

Patented Aug. 9, 1887.

UNITED STATES PATENT OFFICE.

EUGÈNE J. REMILLON, OF MOBERLY, MISSOURI, ASSIGNOR TO THE KANSAS CITY SWITCH AND FROG COMPANY, OF MISSOURI.

SWITCH-STAND.

SPECIFICATION forming part of Letters Patent No. 368,169, dated August 9, 1887.

Application filed November 5, 1886. Serial No. 212,056. (No model.)

To all whom it may concern:

Be it known that I, EUGÈNE J. REMILLON, of Moberly, in the county of Randolph and State of Missouri, have invented a certain new and useful Improvement in Switch-Stands, of which the following is a full, clear, and exact description, reference being had to the accompanying drawings, forming part of this specification, and in which—

10 Figure 1 is a side elevation of my improved stand with part of the housing removed. Fig. 2 is a similar view looking at another side of the stand. Fig. 3 is a vertical section taken on line 3 3, Fig. 1. Fig. 4 is a top view. Fig. 5 is 15 a top view showing the lever in different position from Fig. 4. Fig. 6 is a bottom view. Fig. 7 is a bottom view showing the shaft, crank, or arm in a different position from that shown in Fig. 6. Figs. 8 and 9 are detail elevations, part 20 in section, showing different positions of the crank. Fig. 10 is a top view of the housing. Figs. 11 and 12 are detail views illustrating the manner of holding the sleeve that surrounds the switch-shaft from turning. Fig. 13 25 is a detail view illustrating my invention applied to a switch, where one way the switch is positively locked.

My invention relates to a switch-stand that will hold the switch-points in either position 30 placed, and at the same time will permit the points to be forced over automatically by a train running with the points in case the switch should have been left closed, the device at the same time not interfering with the movement 35 of the switch by hand.

This invention consists in features of novelty hereinafter fully described, and pointed out in the claims.

Referring to the drawings, A represents the 40 housing or frame, supported on a suitable base, B.

C represents the vertical rock-shaft, to which is rigidly secured a collar, D, above the housing, and to the collar is pivoted at E' the operating-lever E, having a slot or opening, E², to receive a lug or projection, I', on a cap, I, that rests on the top of the housing A. When the lever is lowered, the projection I' enters the slot E² to hold the switch closed. On the lower 45 end of the shaft C is a crank, C', to which the switch (not shown) is connected by a rod, C².

Surrounding the shaft is a sleeve, F, enlarged at its upper end, as shown at F', to receive a spring, G, that surrounds the shaft beneath the top of the housing. (See Fig. 3.) The lower 55 end of the sleeve has a base, F², with a depending V-shaped cam, F³, against which bears a friction-roller, C³, on the crank C', the roller, when the switch is in either position, not reaching quite to the base of the cam, as shown in 60 Figs. 8 and 9, so that there will always be a tendency for the cam to hold the switch-points up tight against the main rails, owing to the downward pressure of the spring G on the sleeve F, the points of the switch-rails bearing 65 against the main rails acting to hold the roller C³ from reaching the base of the cam on either side.

The base F² of the sleeve has a semicircular projection, F⁴, extending downward therefrom 70 outside of the cam F³, and the edges of this projection bear against a ledge, A², of the housing, as shown in Figs. 8, 9, and 12, and acts to keep the sleeve from turning, but does not interfere with its vertical movement. The 75 sleeve is held from turning at top by a ledge, A³, on the housing, against which bears a projection, F⁵, on the sleeve. (See Fig. 11.)

The lever E is provided with a cam, E³, that bears against the loose cap I of the housing. 80 When the lever is thrown up into the position shown in Fig. 3, it allows the shaft C to descend until the roller C³ is beneath the point of the cam F³, (see Fig. 3 and dotted lines, Fig. 9,) so that the switch can be moved either way by 85 hand and not be interfered with by the roller coming against the cam. Now, when the lever is lowered into the position shown in Figs. 1 and 2, the shaft is raised again and the pressure of the cam on the roller will hold the 90 switch in whichever position it may be placed; but should the switch be left closed against a main rail and a train approaches from behind or not facing the points, the wheels in wedging between the main rail and the point against it 95 will force the switch-points over, the shaft C being permitted to turn by the upward movement of the sleeve F against the pressure of the spring G, which is caused by the roller C³ bearing against the cam F³. The train is thus 100 allowed to pass through without damage to it or the switch and without danger to the pas-

sengers. The upward movement of the sleeve is indicated by dotted lines in Fig. 1.

In Fig. 13 one-half of the cam only is shown, which is the construction used for a switch 5 where it is desirable to have only one way automatic. The other is positively locked.

The cap is made to turn with the rock-shaft by ears I^2 thereon, that extend upward on opposite sides of the projections D^2 of the collar D , 10 to which the lever E is pivoted.

I claim as my invention—

1. In a switch-stand, the combination of the housing, vertical shaft, cam-lever pivoted to the shaft, sleeve, spring between the upper end 15 of the housing and the sleeve, cam on the lower end of the sleeve, crank on the lower end of the shaft, and friction-roller on the crank, substantially as shown and described, for the purpose set forth.
- 20 2. In a switch-stand, the combination of the housing, vertical shaft, cam-lever pivoted to the vertical shaft, crank on the lower end of the shaft, friction-roller on the crank, sleeve surrounding the shaft, having a base provided

with a downward projection, F^4 , and cam F^3 , 25 and spring G , located between the upper end of the sleeve and the top of the housing, substantially as set forth.

3. In a switch-stand, the combination of the housing having the ledges A^2 A^3 , vertical shaft, 30 cam-lever pivoted to the shaft, crank on the lower end of the shaft, sleeve surrounding the shaft, spring located between the top of the housing and the sleeve, projections F^4 F^5 on the sleeve, and cam F^3 , substantially as set 35 forth.

4. In a switch stand, the combination of the housing, vertical shaft, slotted lever, collar on the shaft which is provided with a projection to which the lever is pivoted, cap on the housing, ears I^2 on the cap engaging the projection on said collar, and projection I' on the cap for entering the slot in the lever, substantially as and for the purpose set forth.

EUGÈNE J. REMILLON.

In presence of—

EDWIN F. MAY,
JAMES STANNARD.
